UNITED STATES PATENT OFFICE.

ALONZO B. WOODARD, OF HORNELLSVILLE, NEW YORK.

DESIGN FOR A FENCE-STRAND.

SPECIFICATION forming part of Design No. 19,974, dated July 1, 1890.

Application filed May 24, 1890. Serial No. 353,099. Term of patent 14 years.

To all whom it may concern:

Be it known that I, ALONZO B. WOODARD, a citizen of the United States, residing at Hornellsburg, in the county of Steuben and State of New York, have invented and produced a new and original Design for Fence-Strands, of which the following is a specification.

This design has for its object to provide a novel, ornamental, and distinguishing fence-strand, and the leading features thereof reside in two longitudinal continuously-undulated lines and lines which alternately run in the reverse diagonal directions and alternately meet at points between the two undulated lines, and right lines extending from such meeting-points across the undulated lines, some of the undulated portions of the latter being between said right lines.

In the accompanying drawings illustrating my design, the figure is a plan view of a portion of a fence-strand.

In the drawing, the reference-numerals 1 and 2 indicate the two longitudinal continuously-undulated lines, and 4 and 6 the lines which alternately run in reverse diagonal directions and meet alternately at the point 7 between the undulated lines. From such meeting-points 7 the right lines 5 extend across the undulated lines, and some of the undulated portions 3 of the latter lines are between the right lines 5.

The peculiar arrangement and form shown presents an ornamental, attractive, and distinguishing appearance.

35

What I claim is—

The design for a fence-strand, substantially as shown and described.

In testimony whereof I have affixed my signature in presence of two witnesses.

ALONZO B. WOODARD.
